UNITED STATES PATENT OFFICE.

HERMAN MARSCHEL, OF BUFFALO, MINNESOTA.

GRAIN-SEPARATOR.

1,198,863.

Specification of Letters Patent. Patented Sept. 19, 1916.

Application filed November 29, 1915. Serial No. 64,072.

To all whom it may concern:

Be it known that I, HERMAN MARSCHEL, citizen of the United States, resident of Buffalo, county of Wright, State of Minnesota, have invented certain new and useful Improvements in Grain-Separators, of which the following is a specification.

The object of my invention is to provide improved means for controlling the direction of flow of the air blast to the end that it may pass through or over the sieves or be partially diverted therefrom and directed through the chaffer for the purpose of carrying away the light refuse material and assisting in the separating operation.

A further object is to provide an attachment for a separator which can be applied without material alteration in the machine.

Other objects of the invention will appear from the following detailed description.

The invention consists generally in various constructions and combinations, all as hereinafter described and particularly pointed out in the claims.

In the accompanying drawings forming part of this specification, the figure is a sectional view illustrating the application of my invention to a separator.

30 In the drawing, 2 represents the frame of a separator, having a sieve shoe 3 for a bank of sieves 4 and a separator shoe 5 for a chaffer 6 to which the straw is delivered from the rack 8.

35 9 represents a fan casing having a blast fan 10 mounted therein.

11 is a plate, preferably of sheet metal, mounted on a block 12 that is supported by links 13 upon arms 14 that are mounted

40 on a shaft 15. By rocking this shaft the arms 14 may be raised or lowered to elevate or depress the end of the plate 11 adjacent to the fan. The other end of the plate 11 is supported on a cross bar 16 and

45 a plate rocks on this bar as a fulcrum when the arms 14 are moved up and down to contract or enlarge the passage between the plate and the top of the casing. Evidently, if the plate is raised to the position indicated by dotted lines this passage or throat,

50 which I will indicate by numeral 17, will be nearly closed and the blast of air from the fan will be directed downwardly by the under surface of the plate toward and through the sieves while, if the plate is lowered to the position indicated by full lines,

the throat will be open sufficiently to allow a considerable portion of the air to pass between the plate and the top of the casing.

Beneath the receiving end of the chaffer 60

I provide a curved plate 18 supported by straps 19 from the chaffer, the inner end of the plate extending under the plate 11 while the opposite end thereof projects upwardly to a point a few inches below the 65

chaffer and serves to deflect the currents of air upwardly into and through the chaffer. When, therefore, the plate 11 is adjusted to allow the currents of air from the fan to pass through the throat 17, the plate 18 will 70

deflect these air currents upwardly through the chaffer and carry away a considerable portion of the light particles of refuse which would otherwise have to be taken care of by the screens beneath. I am thus 75

able to relieve the screens of a considerable portion of their load and greatly increase the efficiency and capacity of the machine. This plate 18 being mounted on or supported by the chaffer, will vibrate therewith 80

within the shoe 3 but independently thereof and also, of course, of the plate 11, the inner end of the plate 18 sliding freely beneath the adjacent end of the plate 11.

I am able by this simple attachment to 85 accurately control the air blast, directing it toward the sieves or toward the chaffer, as preferred to effect a more rapid and better separation than is usually possible in a machine of this type.

90 In various ways the details of construction herein shown and described may be modified and still be within the scope of my invention.

I claim as my invention:

1. The combination, with a vibrating chaffer and a sieve shoe arranged beneath the same and sieves mounted in said shoe, of a fan casing having a throat for directing the blasts of air through said shoe, a deflector mounted to vibrate with said chaffer and means mounted in said throat and cooperating with said deflector to direct a portion of the air through said chaffer, and a portion through said shoe, or substantially 105 all of the air through said shoe.

2. The combination, with a chaffer, a sieve shoe and the sieves mounted thereon, of a fan casing and fan, a deflector mounted to vibrate with said chaffer and direct the currents of air upwardly and through said chaffer, and means for directing the air cur- 110

rents toward said deflector or into said sieves.

3. The combination, with a chaffer and a shoe and sieves therein, of a fan casing and fan having a throat adjacent the receiving end of said chaffer and shoe, a deflecting device mounted to direct a portion of the air from said fan casing into and through said chaffer, and a plate mounted in said 10 throat and lapping by said deflector and having means for tilting it to vary the volume of air directed into said chaffer or to deflect a greater portion of the air from said fan casing into said shoe.
- 15 4. The combination, with a chaffer and sieve shoe and sieves, of a curved deflector mounted adjacent to said chaffer for directing the currents of air therethrough, a fan casing and fan therefor, and a tilting plate 20 mounted to form a continuation of said deflector and direct the currents of air toward the curved wall of said deflector or exclude the air therefrom.
5. The combination, with a chaffer and a 25 sieve shoe and the sieves mounted thereon, of a fan casing and fan, a deflector carried

by said chaffer and vibrating therewith and operating to direct the currents of air upwardly into and through said chaffer and a plate mounted in the throat of said fan 30 casing and adjustable therein for directing the air currents toward said deflector and upwardly into said chaffer or downwardly, away from said deflector into said sieves.

6. The combination, with a chaffer and a 35 sieve shoe and sieves disposed beneath said chaffer and a fan casing and fans having a throat adjacent the ends of said chaffer and sieve shoe, of a deflecting device supported near one end in said throat and having 40 means for raising and lowering its opposite end for tilting said device to direct the air currents passing through said throat, and means adjacent the receiving end of said chaffer and coöperating with said deflecting device to direct a portion of the air into and through the receiving end of said chaffer.

In witness whereof, I have hereunto set my hand this 23rd day of November, 1915. 50

HERMAN MARSCHEL.
